UNITED STATES PATENT OFFICE.

DANIEL C. CAHALANE, OF KEENE, NEW HAMPSHIRE, ASSIGNOR TO W. L. MASON & CO., OF KEENE, NEW HAMPSHIRE.

DESIGN FOR AN INKSTAND.

SPECIFICATION forming part of Design No. 36,318, dated May 12, 1903.

Application filed March 28, 1903. Serial No. 150,067. Term of patent 7 years.

To all whom it may concern:

Be it known that I, DANIEL C. CAHALANE, a citizen of the United States, residing at Keene, in the county of Cheshire and State of New Hampshire, have invented a certain new, original, and ornamental Design for Inkstands, of which the following is a specification.

This new, original, and ornamental design for inkstands is shown in the accompanying drawings, in which—

Figure 1 is a perspective view, and Fig. 2 a top plan view, of an inkstand embodying the design.

15 The base of the inkstand is circular, and from the base the body B curves inwardly, then rises perpendicularly, and the sides are fluted, the concave surfaces C appearing between the ribs D. The flutings terminate at 20 a distance from the base approximating two-thirds of the height of the inkstand. From

the top of the body B the upper part E of the inkstand rises in cylindrical form and is of material contrasting in color with the glass base of the body.

25 Above the cylindrical upper portion E of the inkstand the top curves inward and rises, as at F, and the central dip-cup G extends still farther upward, being flared outwardly at the top, as indicated at H.

30 Having thus described my ornamental design for inkstands, what I claim as new, and desire to secure by Letters Patent, is—

The ornamental design for inkstand, substantially as shown and described. 35

In testimony whereof I affix my signature in presence of two witnesses.

DANIEL C. CAHALANE.
